UNITED STATES PATENT OFFICE.

ROBERT I. PATTERSON, OF MUNCIE, INDIANA.

LOCK.

1,005,295.

Specification of Letters Patent. Patented Oct. 10, 1911.

Application filed December 30, 1910. Serial No. 600,147.

To all whom it may concern:

Be it known that I, ROBERT I. PATTERSON, a citizen of the United States, residing at 116½ East Main street, Muncie, in the county of Delaware and State of Indiana, have invented a new and useful Lock; and I do hereby declare the following to be a full, clear, and exact description of the invention, such as will enable others skilled in the art to which it appertains to make and use the same.

This invention relates to the art of locks and latches and the like, and it more particularly pertains to a new and useful lock, in which there is involved various novel features of construction.

The invention in its broadest scope, aims as its fundamental object, to provide a lock including a gravitating locking member, which may act as an ordinary latch member at one time for temporarily holding a door or the like in a closed position; and then act at other times as a secure locking bolt, which may be thrown into its keeper for permanently and securely locking the door. When the gravitating member acts as a latch, the same may be manipulated easily by the knob of the door; but when the gravitating member is utilized as a locking bolt a key is first utilized for partially withdrawing the gravitating member from its keeper, and subsequently the knob of the door completely withdraws it from the keeper.

A further object of the invention is to provide a practicable, durable, simple and inexpensive springless lock.

Another object of the invention is to provide a lock of this design, embodying means for holding the gravitating member or locking bolt entirely out of operative position.

In the drawings, however, there is disclosed certain forms of the invention, but in practical fields these forms may require alterations, to which the applicant is entitled, provided the alterations are comprehended by the appended claims.

The invention comprises further features and combination of parts hereinafter set forth, shown in the drawings and claimed.

In the drawings:—Figure 1 is a view of a lock, with the front plate removed, to disclose the various features of the invention. Fig. 2 is a similar view, showing the gravitating member or locking bolt arranged in such a position, that the same can-

not be reversed in position without the employment of a key. Fig. 3 is a view similar to Figs. 1 and 2, showing the gravitating member or bolt thrown entirely out of operative position. Fig. 4 is a sectional view on line 4—4 of Fig. 1. Fig. 5 is a view similar to Figs. 1, 2 and 3, showing a modified form of means for manipulating the gravitating member or locking bolt. Fig. 6 is a view similar to Fig. 5, showing the same structure as shown in Fig. 5, with the exception that the gravitating member is thrown entirely out of operative position. Fig. 7 is a view similar to Figs. 5 and 6, showing the different arrangement for manipulating the gravitating member or bolt.

As to the annexed drawings, referring more particularly to Figs. 1, 2, 3 and 4, 1 designates the casing of the lock, through which the knob spindle 2 extends. This spindle 2 is provided with a plurality of teeth 3, which are designed to engage the plurality of teeth or lugs 4 of the disk 5. The disk 5 is loosely and eccentrically mounted upon the knob spindle, and is disposed within the annular opening 6 of the gravitating locking member or bolt 7. In order to permit a door or the like, which may be equipped with a lock of this character, to close without manipulating the knob and its spindle, the extension 8 of the locking member or bolt is beveled as shown at 9. It will thus be seen that as a door or the like is completing its full closed position, the beveled portion 9 of the locking member or bolt contacts with the keeper, thus forcing the gravitating member or locking bolt entirely within the casing of the lock. The gravitating locking member or bolt is pivoted upon a stud 10, which projects from the inner wall of the casing. This stud does not fit a complete annular opening or aperture of the gravitating member, but extends through a slot 11 in the member. The purpose of this slot is to permit the gravitating locking member to be slightly elevated, so that the lug 12 of the gravitating member may be changed from the position shown in Fig. 1, to the position shown in Fig. 2. In other words to arrange the lug 12 on the other side of the lug 13 of the casing, as shown in Fig. 2, so that the gravitating member cannot be withdrawn from its keeper by the knob and its spindle. To arrange the lug 12 in the position shown

in Fig. 2, a key 14 shown in Fig. 2 is inserted in the key hole of the lock, so that the tongue thereof may engage the peripheral edge of the gravitating locking member. Pressure is then applied on the key, which will elevate the gravitating locking member sufficiently to permit the lug 12 to be raised over the lug 13. When the gravitating locking member is disposed as shown in Fig. 2, it cannot be elevated by the knob and its spindle to release it from the position shown in Fig. 2, because of the disposition of the disk 5 with respect to the slot 11. In other words the slot 11 is arranged tangentially with regard to the peripheral edge of the disk 5, thus making it a mechanical impossibility to elevate the gravitating locking member by means of the knob spindle and the disk 5. However, the key as shown in the position in Fig. 2 contacts with the peripheral edge of the gravitating locking member, in such wise as to permit the locking member to move upon the stud 10. The lifting action of the key is approximately at a slight angle 25 with respect to the stud 10, that is, toward the stud when there is an endeavor to elevate the gravitating locking member. When the gravitating locking member is not in the position shown in Fig. 2, but as shown in Fig. 1 the gravitating locking member may be withdrawn from its keeper by means of the disk 5 and its connection between it and the knob spindle. When the disk 5 is moved in a direction to withdraw the locking member, the peripheral edge of the disk 5 gradually contacts with the wall of the opening 6 of the locking member, thus causing the locking member to oscillate upon the stud 10. It will be noted, however, that no 35 pointed instrument, such as a knife blade or the like, can be inserted between the door and its jamb to elevate the gravitating locking member, because the shoulder 14 of the locking member will contact with the edge 40 of the opening 15 in the casing of the lock. 45

To hold the gravitating locking member approximately within the casing of the lock and completely out of operative position a pivoted member 16 is mounted upon the pin 50 17, so as to engage the forward lower corner portion 18 of the gravitating locking member, as shown in Fig. 3. When the locking member completes its movement as shown in Fig. 3 so that the end 19 of the member 55 16 is free to assume the position shown in Fig. 3 the end 20 of the member 16 falls by gravitation.

The front plate 22 of the lock is secured in its place by the screws 23 and the posts 24, 60 in order to hold the mechanism of the lock in place.

In Figs. 5 and 6 practically the same gravitating locking member is disclosed, with the exception that it is of a little different shape. In Figs. 5 and 6 the disk 5 is en-

tirely dispensed with, and the knob spindle is provided with a plurality of teeth or lugs 25, which mesh with the teeth 26 of the inner wall of the opening 6 of the locking member. In these figures the locking member is denoted by the same reference character 7, as in Figs. 1, 2, 3 and 4. The operation of the various parts of the construction of lock shown in Figs. 5 and 6 is identical with that of the other forms, as will be clearly evident. 70

In Fig. 7 the gravitating locking member is pivoted upon the knob spindle, and is rocked by the spindle to withdraw the same from its keeper. In Fig. 7 the knob spindle is designated by the character 28, and is utilized in lieu of the stud 11. The gravitating locking member in Fig. 7 is provided with a slot through which the knob spindle extends. This slot 29 permits the gravitating locking member to be raised by the key 30, in order to dispose the lug 31 upon the other side of the lug 32, in the same manner it is accomplished in the remaining figures of the drawings. 80

From the foregoing it will be clearly noted that there has been provided a durable, simple and efficient springless lock, and one which is practical in every feature, and has been found to fulfill the various requirements. 90

The invention having been set forth, what is claimed as new and useful is:—

1. In a door lock a casing, a pivoted gravitating locking member acting as either a latch or a bolt, means for manipulating the member as a latch, said member being raisable, said member having a sliding action with regard to its pivot, and means for locking the member as a bolt after being raised. 100

2. In a door lock a casing, a pivoted gravitating locking member acting as either a latch or a bolt, means for manipulating the member as a latch, said member being raisable, said member having a sliding action with regard to its pivot when raised, and means for locking the member as a bolt after being raised and means for holding the locking member out of operative position within the casing. 105

3. In a door lock, a casing, a pivoted gravitating disk member having a central opening acting either as a latch or a locking bolt and including a slot through which the pivot of the member extends, means arranged within the central opening for manipulating the member as a latch, said slot constituting means with regard to the pivot for permitting the member to be raised by means of a sliding action on the pivot, means for locking the member after being raised, said member being raisable by means for locking the member. 115

4. In a door lock, a casing, a pivoted gravitating disk member having a central opening acting either as a latch or a locking bolt 120

130

and including a slot through which the pivot of the member extends, means arranged within the central opening for manipulating the member as a latch, said slot constituting

5 means with regard to the pivot for permitting the member to be raised by means of a sliding action on the pivot, means for locking the member after being raised, said member being raisable by means for locking the member, and means for holding the member entirely out of operative position and within the casing.

5. In a door lock, a casing, a locking member arranged in the casing including a central annular opening, and provided with a slot, a pivot for the member extending through the slot, so that the member may pivot or slide thereon, a spindle extending transversely of the casing and eccentrically 20 through the central opening and provided with an eccentrically mounted disk, to sweep against the annular wall of the opening for manipulating the member as a latch, said spindle including cog connections with the eccentrically mounted disk for moving it, said slot constituting means whereby the member may be raised through a sliding action on the pivot, means for locking the bolt after being raised, and means for holding 30 the locking member entirely out of operative position within the casing.

6. In a lock, a casing, a pivot pin extending transversely thereof, a gravitating member slidably pivoted on the pin thus constituting a combined latch and bolt, said member being held closed as a latch by gravitation, and a gravitating device engageable automatically with the member for holding the member out of operative position.

40 7. In a lock, a casing, a pin arranged transversely thereof, a gravitating member slidably mounted thereon held normally into

operative position by gravitation, and a gravitating device automatically engageable with the member for holding the same out of 45 operative position.

8. In a lock, a casing, a pin therein, a gravitating member mounted thereon held normally into operative position by gravitation, and a gravitating device automatically engageable with the member to hold it out 50 of operative position against its gravitation.

9. In a lock, a casing, a pin therein, a gravitating member slidably mounted thereon thus constituting a combined latch and bolt, said member being held closed as a latch by gravitation, a gravitating device automatically engageable with the member for holding the same out of operative position as a latch, said gravitating device being 60 manually manipulated to release the member.

10. In a lock, a casing, a pin therein, a gravitating member slidably mounted thereon thus constituting a combined latch and bolt, said member being held closed as a latch by gravitation, a gravitating device automatically engageable with the member for holding the same out of operative position as a latch, said gravitating device being 65 manually manipulated to release the member, said member being raisable by virtue of the sliding action relative to the pin so as to lock the member as a bolt, and means for holding the member locked as a 70 bolt.

In testimony whereof I have signed my name to this specification in the presence of two subscribing witnesses.
